(57) **CLAIM**

The ornamental design for a flexible ice-film with cold storage fluid, as shown and described.

DESCRIPTION

FIG. 1 is a top, front and right-side perspective view of the flexible ice-film with cold storage fluid showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom, rear and left-side perspective view thereof; and,

FIG. 9 is an enlarged view, of circled portion 9, of FIG. 1, thereof.

The broken lines throughout the drawing figures depict portions of the flexible ice-film with cold storage fluid that form no part of the claimed design.

The dot-dash broken lines depict the boundaries of the FIG. 1 and 9 enlargement that forms no part of the claimed design.
